design No. 534

*Knapp & Neals' Design for a
Union Coal Burner.*

Patented Dec 14, 1852.

Gilbert Knapp & Adnah H. Neal of Homedale Pa.
Letter Patent No 534, Dated Dec 14th 1852.

The schedule referred to in this Letter Patent and making part of the same

To all whom it may concern:

Be it known that we, Gilbert Knapp, and
Adnah H. Neal, of Homedale in the County of Wayne, and State
of Pennsylvania, have invented a new ornamental Design for a stove,
called the

Union Coal Burner;

and we do hereby declare
that the following is a full, clear and exact description of the same refer-
ence being had to the accompanying drawings, forming part of this
specification, in which

Fig. 1. is a horizontal section of the stove, taken through
the line a. a. in Fig. 2. the door being open.

Fig. 2. is a side elevation of the stove complete.

Fig. 3. is a sectional profile of the same.

The same letters of reference in each of the several Figs
indicate corresponding parts.

The body A of the stove, consists of a corrugated cylinder, similar to that shown in section in Fig. 1. around the centre of the periphery of which a number of apertures B.B. of an ornamental configuration similar to that shown in Fig. 2. of the drawing are made. - and around the top and bottom of this corrugated cylinder, there are mouldings C.C. of the form of a torus; in and around the bottom one C. of which apertures D.D. of an ornamental outline similar to that shown in Fig. 1 and 2 are formed. - The door E. of the cylinder A, also has apertures F.F. G. G. and H.H. of an ornamental configuration similar to that shown in the drawing Fig. 2 cut in it.

The base or bottom I, upon which the stove rests, is

of a shape precisely similar to that shown in Figs 1 and 2, the shape of the mouldings being more clearly illustrated in Fig. 3, of the drawings. The draft door *T*, has four oblong apertures in it, around the edges of which a lead *a, a*, is formed, as shown in Figs 1 and 2; between two of which apertures an opening of an elliptical shape is formed around which there is also a lead or torus *b*.

The top plate *K*, which surrounds the body of the stove, in the manner shown in Fig. 3, is ornamented with mouldings *c, d*, of similar shape as that shown in Figs 2 and 3, and the cap or cover *K'*, is also of an ornamental shape, it being ornamented with mouldings *g, h*, similar in shape or configuration as those shown in Fig. 3.

The feet are of the form of a cima recorta.

What I claim as my invention and desire to secure by Letters Patent, is

The ornamental design and configuration of the stove *A*, & door *T*; and also the ornamental openings *B, B, D, D, E, E, G, G, and H, H*, in combination with the different mouldings as hereinafter shown and described.
